UNITED STATES PATENT OFFICE.

JEAN U. KORÉE AND ASSAD M. MALLUK, OF NEW YORK, N. Y., ASSIGNORS TO INTERNATIONAL PATENT INVESTMENT CORPORATION, OF NEW YORK, N. Y., A CORPORATION OF DELAWARE.

VACUUM CONTAINER.

Application filed June 13, 1922, Serial No. 567,932. Renewed December 27, 1924.

To all whom it may concern:

Be it known that we, JEAN U. KORÉE, a subject of the King of Rumania, residing at and whose post-office address is No. 1834 5 Broadway, in the city, county, and State of New York, and ASSAD M. MALLUK, a citizen of the Republic of France, residing at and whose post-office address is No. 170 West 72nd Street, in the city, county, and State 10 of New York, have invented certain new and useful Improvements in Vacuum Containers; and we do hereby declare the following to be a full, clear, and exact description of the invention, such as will enable 15 others skilled in the art to which it appertains to make and use the same.

This invention relates to vacuum containers, and has for one object the provision, in a single unitary structure, of means for carrying two liquids or solids having widely different temperatures, and for preserving these temperatures during a substantial period of time.

Another object of the invention is to provide means for effectively protecting such containers against the breaking of the fragile vacuum receptacle, or vessel, under certain conditions.

In order to attain these objects we provide a two compartment vacuum insulated receptacle, of glass, or other suitable material, the compartments being arranged end to end, and having a single common vacuum space separating them. Both compartments 30 must hold a reasonable amount of food, and it is necessary, therefore, that the container as a whole be made somewhat larger than the usual vacuum containers. It has been found preferable to increase the length of 35 the structure rather than the diameter, but, inasmuch as this increase in length weakens the structure, it is desirable to provide some means for reinforcing the receptacle at its center opposite the common vacuum space. 40 The double compartment vacuum insulated receptacle is inserted within a protective casing of metal, which casing is also provided with a reinforcing ring centrally disposed with respect to its ends.

In vacuum containers as at present constructed, if one is accidentally allowed to fall upon the ground, striking on its side, the vacuum receptacle which is more or less fragile, will in the majority of cases be

broken by the fall. We have discovered 55 that the liability of breakage in this manner may be greatly reduced by the provision of resilient protective members, comprising rods or strips which are more or less flexible, running longitudinally of the casing 60 and detachably mounted on the exterior about mid-way between the ends of the casing. If a container thus protected should be accidentally dropped and the container strike upon its side, on account of the shape 65 of the resilient protective members, their ends will strike first and the greater portion of the shock will be absorbed by the flexing of these members, and, in some cases, in detaching them from the casing. 70

These resilient protective members may conveniently be made in the form of eating utensils, such as knives, forks and spoons, thereby serving a double purpose.

Although this means for protecting a 75 vacuum container may be used with one having a single compartment, its greatest use is in connection with the double container inasmuch as it is necessary to provide extraordinary means to prevent breakage. 80

In the accompanying drawings we have illustrated our invention in connection with a vacuum container of the bottle type, that is, both of the compartments are provided 85 with openings which are more or less restricted. It will be understood, however, that either one or both of the compartments of this container may be constructed with openings which are less restricted in order to facilitate the introduction of solid food 90 instead of liquid.

In these drawings:

Fig. 1 is a longitudinal sectional view of our improved double compartment container, and

Fig. 2 is a view in transverse section taken on line 2-2 of Fig. 1, showing the distribution of the resilient protective members around the periphery of the container.

In these drawings the vacuum insulated receptacle is indicated at 3 and is provided with the separate food compartments 4 and 5. This receptacle, or vessel, is insulated against the passage of heat either to or from the vessel in the ordinary manner, that is, by means of double walls 6 and 7 with the space 8 intermediate these walls evacuated. The common insulating space 9 which sepa-

rates the compartments 4 and 5 is in communication with the space 8 so that the vessel may be evacuated by connection with the vacuum pump at a single point and the vessel can, therefore, be sealed by means of a single seal. In order to support the interior ends of the compartments 4 and 5, it is necessary to join the wall 6 with the wall 7 at a relatively few points as indicated 10 at 10.

Another very satisfactory means of supporting the compartments is by the use of an elastic ring of cork, or similar material, interposed between the walls 6 and 7.

15 As mentioned above, on account of the length of the vacuum receptacle 3 and the fact that the inner wall 6 is not continuous from end to end, it is desirable to reinforce the receptacle by means of an exterior band 20 12 of cork, vulcanized rubber, or the like.

13 represents the protective metal casing which surrounds the vacuum vessel into which the vessel may be inserted or removed by unscrewing the section 14 at the threads 25 15. Washers 16 are provided at each end of the vacuum receptacle which, in cooperation with the band 12 resiliently support the vacuum vessel within the metal casing 13.

30 It is very desirable to reduce the weight of the container as much as possible, and on this account the metal casing 13 is made relatively thin and is reinforced midway between its ends by means of ring 16' of 35 relatively light, strong elastic material, such as hard rubber.

We now come to the auxiliary or supplemental means for protecting the container which comprises the resilient members 17 40 suitably spaced around the outside of the casing 13 as clearly shown in Fig. 2. These resilient protective members are detachably mounted upon the casing 13 about midway between the ends thereof, and may be conveniently secured to the protecting ring 16. The means for attaching the members 17 to ring 16 preferably comprises a pair of snap fasteners 18 for each member which effectively secures the members 17 to the container, but at the same time offers some 50 considerable resistance to the detachment of the members so as to assist in absorbing the shock due to the fall of the container. The members may, however, be detached with the fingers with comparative ease. As 55 shown in the drawings these resilient protective members are made in the form of knives, forks and spoons, there being two of each of these articles.

60 Each of the food compartments 4 and 5 is provided with the usual stopper 19 of cork, or other suitable material, and these stoppers, as well as the ends of the vacuum vessel are protected by means of the metal caps 20 which are of such size and shape

that they also serve the purpose of drinking cups.

With the vacuum container constructed in accordance with our invention either liquid or solid food, or a combination of the two may be preserved at approximately the temperature at which they were originally introduced into the container for a considerable number of hours, and if the container is accidentally dropped, landing upon its side, the shock of the fall is materially reduced by the auxiliary protecting members provided. Moreover, these members may be used as eating utensils. Furthermore, the construction of the two food compartments in a single unitary structure having a single exterior wall and separated by a common vacuum space considerably reduces the cost of manufacture on account of the saving in material, and the saving of one operation of exhaustion.

It is to be understood that the size and proportions of the various parts may be varied without departing from the principle of the invention which is not limited to the particular embodiment shown and described, but is intended to include such modifications thereof as fall within the scope of the appended claims.

We claim:

1. In a device of the class described, a vacuum vessel having an outer wall and an inner wall formed into a plurality of compartments placed end to end, said compartments being held in spaced relation with said outer wall by a plurality of rigid supports disposed near the inner ends of said compartments, a protecting casing surrounding said vessel and in spaced relation thereto, a protective member on the inside of said casing, and a second protective member on the outside of said casing, both of said protective members being disposed opposite said rigid supports.

2. In a device of the class described, a vacuum vessel having an outer wall and an inner wall formed into a plurality of compartments placed end to end, said compartments being held in spaced relation with said outer wall by a plurality of rigid supports disposed near the inner ends of said compartments, a protecting casing surrounding said vessel and in spaced relation thereto, a protective member of resilient material on the inside of said casing, and a second protective member on the outside of said casing, both of said protective members being disposed opposite said rigid supports.

3. In a device of the class described, a vacuum vessel having an outer wall and an inner wall formed into a plurality of compartments placed end to end, said compartments being held in spaced relation with said outer wall by a plurality of rigid supports disposed near the inner ends of said

compartments, a protecting casing surrounding said vessel and in spaced relation thereto, a protective member on the inside of said casing, and a second protective member on the outside of said casing, both of said protective members being disposed opposite said rigid supports, and flexible auxiliary protective members mounted on the outer protective member.

- 10 4. In a device of the class described, a vacuum vessel having an outer wall and an inner wall formed into a plurality of compartments placed end to end, said compartments being held in spaced relation with
- 15 said outer wall by a plurality of rigid sup-

ports disposed near the inner ends of said compartments, a protecting casing surrounding said vessel and in spaced relation thereto, a protective member on the inside of said casing, and a second protective member on the outside of said casing, both of said protective members being disposed opposite said rigid supports, and flexible auxiliary protective members detachably mounted intermediate their ends on the outer protective member.

In testimony whereof we affix our signatures.
